(57) **CLAIM**

The ornamental design for an external electronics housing, as shown and described.

DESCRIPTION

FIG. 1 is a first perspective view of the external electronics housing;

FIG. 2 is a second perspective view of the external electronics housing;

FIG. 3 is a front view of the external electronics housing of FIG. 1;

FIG. 4 is a rear view of the external electronics housing of FIG. 1;

FIG. 5 is a right side view of the external electronics housing of FIG. 1;

FIG. 6 is a left side view of the external electronics housing of FIG. 1;

FIG. 7 is a top view of the external electronics housing of FIG. 1;

FIG. 8 is a bottom view of the external electronics housing of FIG. 1;

FIG. 9 is an perspective view of the external electronics housing of FIG. 1 attached to a container; and,

FIG. 10 is an enlarged view of the perspective view of the external electronics housing taken from FIG. 9.

In the accompanying drawings, the evenly-spaced broken lines in the figures depict portions of the internal electronics housing that form no part of the claimed design and/or depict the nature and environmental use of the claimed design. The dot-dot-dash broken lines encircling portions of the claimed design that are illustrated in the enlargement form no part of the claimed design.
